Diederheim Fairbanks

ATTORNEYS.

UNITED STATES PATENT OFFICE.

EDGAR A. GILLINDER, OF PHILADELPHIA, PENNSYLVANIA.

INTERCHANGEABLE GLOBE HOLDER FOR AN ELECTRIC LIGHT.

1,425,852.

Specification of Letters Patent. Patented Aug. 15, 1922.

Application filed December 13, 1921. Serial No. 522,083.

To all whom it may concern:

Be it known that I, EDGAR A. GILLINDER, a citizen of the United States, residing in the city and county of Philadelphia, State 5 of Pennsylvania, have invented a new and useful Interchangeable Globe Holder for an Electric Light, of which the following is a specification.

My invention relates to an electric light 10 fixture and has for its object an attachment for supporting a globe, bowl or shade of larger size on the collar than exists on the fixture heretofore employed for supporting a globe, bowl or shade of less size.

To this end I employ a supplemental 15 collar forming an interchangeable holder which is attachable to the existing collar and is of such diameter that a globe, bowl or shade of larger diameter may be connected with said existing collar, and permit 20 the latter to enter the upper wall of said supplemental collar and adapt its screws to be employed to secure the supplemental collar to said existing collar.

The invention is satisfactorily illustrated 25 in the accompanying drawings, but the important instrumentalities thereof may be varied, and so it is to be understood that the invention is not limited to the specific 30 details shown and described, as long as they are within the spirit or scope of the claims.

Figure 1 represents a side elevation partly broken away of an interchangeable 35 holder or supplemental collar for an electric light embodying my invention, including the electric light fixture and a globe, bowl or shade attached to said collar.

Figure 2 represents a vertical section of 40 said collar, including other features in dotted lines.

Figure 3 represents a top plan view of the collar.

Similar numerals of reference indicate corresponding parts in the figures.

Referring to the drawings.

1 designates an electric light fixture and 2 designates the electric light shown in dotted lines adapted to be screwed to the socket of the fixture.

50 3 designates the collar on the socket provided with screws 4 for holding a globe, bowl or shade of usual size suspended from the socket, these features per se being well known in the art.

5 designates the supplemental collar 55 which is of considerably greater diameter than said collar 3 and is of the form of a circular hollow body consisting of the top wall 6, the opening 7 therein, the side or side wall 8 depending from the periphery 60 of said top wall, the neck 9 which rises from the wall of the opening 7, and the screws 10 in said sides, the top wall 6 being depressed around the neck forming the circular channel 11.

65 12 designates a bowl, globe or shade of greater diameter than the usual bowl globe or shade which was previously retained on the collar 3 by the screws 4 and which for purpose of clearness has been removed, but 70 which is substituted by the larger size bowl 12, when the latter is desired for use.

75 It will now be seen that the collar 3 is utilized to support the collar 5, and the latter is employed to carry the bowl 12, hence said bowl is passed upwardly over the light 2, this being permitted by the opening 7. Then the neck 9 of the collar 5 enters the collar 3 from below and the channel 11 receives the base portion of the 80 collar 3 and its screws 4, thus positioning the screws 10 of the collar 5 for subsequent engagement with the neck of the bowl 12, as hereinafter further explained. The screws 4 are now tightened against the neck 85 9 thus connecting the collar 5 with the collar 3. The neck 13 of the bowl 12 is now inserted into the collar 5 from below and the screws 10 are tightened against the outer side of the top neck of the bowl 12, 90 see Figure 2, and so the bowl is connected with the collar 5 and suspended from the collar 13 and consequently from the lighting fixture.

95 It is evident that when the screws 10 are loosened, the bowl 12 may be removed from the collar 5, and when the screws 4 are loosened, the collar 5 may be removed from the collar 3 then if desired a bowl, globe or shade of less size or diameter may 100 be fitted in the collar 3 and secured thereto by the screws 4. Again by removing said bowl from the collar 3, the collar 5 may be connected with the former and the bowl 12 connected with the collar 5, and so supporting the same, as hereinbefore described.

105 It is evident that the bowl 12 may first be connected with the collar 5 and carried

by the same, and then fitted to the collar 3, the former passing over the light 2, owing to the opening 7, when the screws 4 are tightened, the result being the same as previously stated.

Having thus described my invention what I claim as new and desire to secure by Letters Patent, is:—

1. An interchangeable globe holder for an electric light consisting of a collar adapted to have a globe of large diameter held thereon, and means on said collar for connecting it with the collar on the fixture of the light with which a globe of less diameter is adapted to be held, the former named collar having in its top wall a channel in which the base of the light-fixture may be seated.
2. In an electric light, a globe holding collar on the fixture thereof, and an auxiliary globe holding collar adapted to be connected with the first named collar, said collars being of differential diameters, said auxiliary globe holding collar having in its top wall a channel in which the base portion of the collar of the fixture is adapted to be seated.
3. In an electric light, an auxiliary collar for holding a globe of large diameter on the collar of the fixture of the light adapted to hold a globe of less diameter, said auxiliary collar consisting of a hollow body having a top wall, a neck centrally thereon, and a depending side, said neck being adapted to be connected with said collar of the fixture, said side wall having means for connection of the globe of larger diameter, and said top wall having therein a channel in which the

base portion of the collar of the fixture is adapted to be seated.

4. An auxiliary collar for an electric light fixture consisting of a hollow body formed of a top wall, and a depending side wall on the periphery thereof, a central opening in said top wall, and a neck rising from the wall of said opening, means on said neck for attaching said auxiliary collar to an existing collar of less diameter on said fixture, and means on the side of said body for connecting a neck of a globe of greater diameter with said auxiliary collar, said top wall of the auxiliary collar having therein between its central neck and depending side a channel in which the base portion of the fixture collar is adapted to be seated.

5. An auxiliary collar for an electric light fixture consisting of a hollow body formed of a top wall, and a side on the periphery thereof, an opening in said top wall, and a neck rising from the wall of said opening, means on said neck for attaching said auxiliary collar to an existing collar of less diameter on said fixture, means on the side of said body for connecting a neck of a globe of greater diameter with said auxiliary collar, the top wall of said auxiliary collar having therein a channel adapted to have the base portion of the existing collar on the fixture seated therein.

EDGAR A. GILLINDER.
